UNITED STATES PATENT OFFICE

2,533,882

SWINGABLE PROP FOR CONVEYERS

Earl H. Ensinger, Cleveland, Ohio

Application August 2, 1946, Serial No. 687,883

5 Claims. (Cl. 198—233)

1

My invention relates to portable conveyors of a type adapted to be carried on a truck or other vehicle and designed for use in handling materials such as coal, stone, and the like, in the loading and unloading of such vehicles. Conveyors of this type are designed for manual handling by one or two persons and are therefore of relatively light weight and easily portable.

My invention consists of the provision of this type of portable conveyor with novel swingable wheeled prop means which are positionable by gravitational action to a position supporting the conveyor unit in a raised position and which are also positionable by gravitational action to a position supporting the conveyor unit in a lowered position.

My invention involves a novel construction of the prop means such that the positioning of the prop unit by gravitational action to either of its positions is accomplished merely by the raising and manipulation of one end of the conveyor unit manually by one person. In the position of the prop unit in which it is capable of supporting the conveyor device in lowered position, the prop unit is folded adjacent the conveyor device and means are provided for locking the wheeled prop unit in this condition for carrying of the conveyor unit on a truck or other vehicle.

Other objects, advantages, and features of the invention will appear from the following detailed description and accompanying drawings, in which:

Figure 1 is a side elevation of a conveyor device embodying my invention and illustrating the same with the prop unit disposed so as to support the conveyor device in raised condition.

Figure 2 is a side elevation, partly broken away, showing the conveyor device with the prop unit in folded condition.

Figure 3 is a section taken substantially on the line 3—3 of Figure 1.

Figure 4 is a section taken substantially on the line 4—4 of Figure 3.

Now referring to the drawing and describing the invention in detail, the conveyor unit, generally designated A, has a detachable motor unit, generally designated B, mounted thereon, and is provided with a swingable prop unit designated C. The conveyor unit A comprises a metal frame 1 extending substantially the length of the conveyor unit and carrying the side members 2 secured to the main frame 1 and angularly disposed with reference to said main frame as shown best in Figure 3. The frame 1 and side members 2 support the endless belt 3 which is

2

driven so as to run lengthwise of the conveyor unit A by suitable means including the motor unit B, belt 4, and chain drive 5.

The motor unit B is mounted upon suitable supporting members 6 secured to the main frame 1. The rear end of the conveyor unit is provided with a hopper 7 and a skid plate 8 for supporting that end of the conveyor unit upon the ground.

The swingable prop unit C comprises a hanger member 9 formed of sheet metal to provide a transverse web portion 10 and angularly disposed side portions 11 and 12 provided with the outwardly flanged portions 11a and 12a. The side portions 11 and 12 of the hanger 9 are of generally triangular shape, of greater width at their upper edges and tapering down to a narrower width at their lower edges adjacent the lower extremity of the hanger member 9. The hanger 9 is pivotally mounted on a cross shaft 13 extending transversely of and carried by the main frame member 1. Shaft 13 also extends through certain of the motor supporting members 6 to provide a more rigid mounting of the shaft 13 to the frame of the conveyor. The ends of said shaft 13 extend through apertures in the side portions 11 and 12 in the hanger 9, said apertures being located in the upper corners of said side portions adjacent the web portion 10. The corners of the side portions 11 and 12 containing the apertures receiving the ends of the shaft 13 extend above the upper edge of the web portion 10 as will be clearly seen from the drawing. A reinforcing cross brace member 14 extends across the web 10 adjacent the upper edge thereof, said cross brace 14 being welded or otherwise suitably secured to the web 10.

Welded or otherwise suitably secured to the bottom edge of the hanger 9 is a crossbrace member 15 to which are similarly secured the U-shaped wheel carrying bracket members 16 and 17. Wheels 18 and 19 are rotatably carried by the latter bracket members 16 and 17 by means of suitable axles 20 and 21 extending between the sides of said bracket members 16 and 17. From the lower end of the hanger 9 there extends a lug 22 having an aperture for receiving the hooked end of a locking member 23 which is pivotally carried by a lug 24 secured to the frame of the conveyor.

By virtue of the provision of the triangular tapered side portions 11 and 12 the weight of the hanger is so distributed as to provide a gravitational force upon the hanger 9 eccentrically of and to the rear of the shaft 13 which tends to counterbalance the weight of the wheels at the

lower end of the hanger, so that when the swinging prop unit C is in the position of Figure 2 and subsequently disengaged from the locking member 23, the said swinging prop unit will swing to the position illustrated by Figure 1 in which the axis of the wheels is disposed forwardly of the axis of pivotal connection 13 of the hanger 9 to the frame of the conveyor.

In use the swingable prop unit C can be disposed in the position illustrated by Figure 2 for transporting of the conveyor device upon a truck or other vehicle. The prop unit C may be locked in this position by engagement of the hooked portion of the lock member 23 with the lug 22. In this position the upper edge of the web 10 will engage the frame of the conveyor to prevent further clockwise swinging movement of the prop unit beyond the position shown in Figure 2; hence in the locked position of the prop unit as shown in Figure 2, the wheels 18 and 19 when resting upon the ground will support the conveyor device in nearly horizontal position—that is to say, in a lowered position in which the conveyor may be moved about supported upon its wheels and the skid plate 8. Assuming that the prop unit C is in the position of Figure 2 and that the conveyor device is supported by the skid plate 8 and the wheels 18 and 19 resting upon the ground, and that it is desired to dispose the conveyor device in the position of Figure 1 (which is the normal position of the conveyor device when the same is to be used for handling of materials to and from a truck or other vehicle), it is only necessary to disengage the lock member 23 from its connection with the lug 22 and then raise the forward end of the conveyor to approximately the position occupied in Figure 1. Under such conditions the prop C will swing from the position of Figure 2 to the position illustrated by Figure 1, in which the wheels 18 and 19 resting on the ground will support the carrier device in raised position. Now when it is desired to dispose the prop unit in collapsed condition of Figure 2, and assuming the conveyor device is in the position illustrated in Figure 1, it is only necessary to raise the forward end of the conveyor device so that the same is supported upon the ground only by the skid plate 8 and so that the prop C will swing free from engagement of the wheels 18 and 19 with the ground. Under such conditions, the wheels being forwardly of the pivotal axis 13, the prop C will swing to a position in which the wheels are rearwardly of the pivotal axis 13, and if the forward end of the conveyor is at such latter time lowered so that the wheels 18 and 19 engage the ground, the prop unit will collapse to the condition of Figure 2 with the wheels 18 and 19 closely adjacent the conveyor frame, and thus the conveyor device is disposed in lowered position supported upon the wheels 18 and 19 and the skid plate 8. In this condition the lock member 23 may be engaged with the lug 22 to maintain the prop unit in collapsed condition for transporting of the conveyor device upon the carrier vehicle.

It will be apparent from the foregoing that the upper edge of the web 10, or that edge adjacent the pivotal axis 13, together with the cross plate 14, provides engaging means engaging the frame of the conveyor for limiting the swinging movement of the prop in either direction about the pivotal axis 13. In this connection it may also be noted that this engaging or limiting means is disposed adjacent to and below the pivotal axis 13 of the prop and to one side of the vertical

plane of said pivotal axis in the direction of swinging movement of the prop. This permits the prop to swing to the position of Figure 1 in which the lower end of the prop is disposed slightly forwardly of the pivotal axis 14 for supporting the conveyor in a raised position and also permits the prop to swing to the position of Figure 2 in which the lower end of the prop is disposed a considerable distance rearwardly of the pivotal axis 13 for the collapsed or folded condition of the prop.

It may be noted that the conveyor device is of very light-weight construction, rendering same easily manipulatable and portable by one or two persons. Manipulation of the conveyor to swing the prop C to either of its primary positions will usually consist of raising the forward end of the conveyor device, with the rear end of the conveyor supported by the skid plate resting on the ground, and when the prop C is free of the ground, a quick upward or downward shaking movement may be imparted to the forward end of the conveyor to assist the swinging movement of the prop, and as soon as the prop C swings approximately to one of its primary positions, the forward end of the conveyor is lowered so that the wheels 18 and 19 contact the ground, and the weight of the conveyor will then carry the prop fully to the desired position.

Having thus described my invention, what I claim as new and desire to secure by Letters Patent of the United States, is:

1. In a portable materials handling conveyor unit of the class described, in combination, a conveyor including a frame, a prop swingably mounted on the frame for free swinging movement below the frame in either direction toward either of the opposite ends of the frame, engaging means on the prop to engage the frame at one point to hold the prop in upright condition for supporting the frame in elevated position and to engage the frame at another point when the prop is swung toward the other end of the frame for supporting the frame in a lowered position, and wheels on the free end of the prop to support the frame in either raised or lowered position.

2. In a portable materials handling conveyor unit of the class described, in combination, a conveyor including a frame and having a charging end and a discharging end, a swingable prop pivotally connected to said frame intermediate said charging and discharging ends to hang below the conveyor for free swinging movement relative thereto for supporting the same with respect to a surface on which it is disposed, either in a position with the discharge end raised or in a position with the discharge end lowered, and engaging means on said prop engageable with said frame at one point to limit the swinging movement of the prop relative to said frame in the direction of the discharge end to a position in which the lower end of the prop is disposed between its pivotal axis and the discharge end for supporting said conveyor in said raised position, said engaging means being engageable with said frame at another point to limit swinging movement of the prop in the opposite direction toward the charging end to a position in which the lower end of the prop is disposed adjacent the frame for supporting said conveyor in said lowered position.

3. A portable conveyor as claimed in claim 1, wherein the prop is pivotally connected to the frame, said prop having a weighted portion eccentric to the pivotal axis thereof tending to

counterbalance the free end of the prop and cause swinging movement thereof toward its said upright condition.

4. A portable conveyor as claimed in claim 1, wherein the prop is pivotally connected to the frame and comprises side portions of generally greater width at the ends thereof adjacent the pivotal axis of the prop and tapering to a narrow width at the free ends of said side portions whereby to provide said prop with weighted portions eccentric to said pivotal axis tending to counterbalance the free end of the prop and cause swinging movement thereof toward its said upright condition.

5. In a portable materials handling conveyor unit of the class described, in combination, a conveyor including a frame, a prop swingably mounted on the frame for free swinging movement below the frame in either direction toward either of the opposite ends of the frame, said prop comprising transversely spaced side members and a transversely extending cross member interconnecting said side members below the frame and disposed adjacent to but spaced from the swinging mounting of the prop to engage the

25

frame at one point to hold the prop in upright condition for supporting the frame in elevated position and to engage the frame at another point when the prop is swung toward the other end of the frame for supporting the frame in a lowered position, and wheels on the free end of the prop to support the frame in either raised or lowered position.
